UNITED STATES PATENT OFFICE.

JOHN C. HARDENBERGH, OF CLEVELAND, OHIO, ASSIGNOR OF ONE-FOURTH TO EDWIN S. GAYLORD, OF CLEVELAND, OHIO.

TRAIN-CONTROLLING DEVICE.

No. 813,887.

Specification of Letters Patent.

Patented Feb. 27, 1906.

Application filed May 29, 1905. Serial No. 262,710.

To all whom it may concern:

Be it known that I, JOHN C. HARDENBERGH, a citizen of the United States, residing at Cleveland, in the county of Cuyahoga and State of Ohio, have invented a certain new and useful Improvement in Train-Controlling Devices, of which the following is a full, clear, and exact description, reference being had to the accompanying drawings.

10 The object of this invention is to provide a very simple and effective device adapted to be located at desired points along a railway-track to automatically signal the engineer or stop the train.

15 My device is connected with a block-signal system, either in addition to the semaphores or as a substitute for them. It is arranged to be thrown to idle position from the signal-tower whenever the signal is at "safety."

20 The invention consists in a very simple spring-trip, hereinafter more fully described, which is located between the rails and is adapted to stand in the path of a lever on the locomotive which operates the signal or applies 25 the brake. Coöperating with the spring-trip is a rock-shaft arranged with an arm so that the spring may be drawn down and held at idle position whenever "safety" is indicated.

20 My trips are designed to be placed both at 30 the danger-signal and at the cautionary signal, and the lever which the trip operates is also under the control of the engineer, so that if the cautionary signal applies the brake the engineer can throw it off, simply resulting in 35 the desirable slackening of speed.

35 In the drawings, Figure 1 is a side elevation of a track equipped with my device and showing an approaching locomotive. In this figure the semaphores are turned at right angles to their real positions for convenience of illustration. The trip nearest the locomotive corresponds to the cautionary signal and the one farther in advance thereof to the danger-signal, the cautionary trip being shown 40 as in active position and the danger-trip as inactive, the danger-signal being at "safety." Fig. 2 is a perspective view of the trip and its operative rock-shaft associated with a signal. Fig. 3 is a plan of the track, showing a 45 pilot of an approaching locomotive. Fig. 4 is a bottom plan of such pilot. Fig. 5 is a perspective view of the air-valve on the locomotive, which the trip operates.

My trip consists of a spring-metal bar A, bent into a shape presenting an upward bulge and bent under legs as the approximately elliptical or diamond shape. (Shown in Figs. 1 and 2.) The spring-bar is preferably flat before bending. At the base of its legs a are inwardly-projecting feet a', by which it is secured to a plate B, which rests upon and is secured to the ties C. Suitable slots a² in the feet a' allow the trip to be adjusted in position. The tendency of the spring action of the trip is to cause it to assume the position shown in Fig. 2 or that of the left-hand trip in Fig. 1. In this position the trip projects up somewhat into the path of the pilot of the locomotive. The pilot D preferably carries on the under side of its point a plate d, in which is journaled a roller d'. This allows the pilot to pass easily over the trip, the trip being thereby depressed and springing back into position after the pilot has passed.

Behind the pilot at some suitable point on the locomotive is a depending arm E, which is arranged to automatically apply the brake or to operate a signal in the cab and to initiate any other operations which may be desired. This arm depends sufficiently so that the trip when in its elevated position is in its path and engages the arm as the locomotive passes over the trip. This engagement swings the arm to apply the brake or give a signal.

To hold the trip inoperative, I provide a rock-shaft F, suitably journaled parallel with the ties which carry the trip. On its inner end this rock-shaft has a hooked arm f, which extends through a slot in a bar a³, depending from the upper plate of the trip. The outer end of the rock-shaft F is provided with a suitable crank-arm f'. When this crank-arm f' is moved in the proper direction, (toward the right in Figs. 1 and 2,) the hook f is swung to draw down the trip into idle position. (Shown at the right-hand end of Fig. 1.) The bar a³ is slotted, so that the trip may be depressed by the pilot without interfering with the hook f. It will thus be apparent that a force applied to the crank-arm f' can draw the trip down into idle position and hold it there, while in the absence of such action the trip stands ready to engage the arm E of any approaching locomotive.

The connection from the arm f' which throws the trip to idle position, may lead di-

rectly to the signal-tower, the trip taking the place of the ordinary semaphore, or the semaphore may still be employed and the crank-arm f' simply coupled to it, the same rod or wire operating them both. This is the installation shown in the drawings. In Fig. 1, G' represents the distant or cautionary semaphore, and G² the danger-semaphore. In Fig. 2 either semaphore is indicated by G. The blades of these semaphores may be counterweighted to cause them to normally stand at active position. A wire g may lead downward therefrom to the crank f' , and from the same crank a wire g^2 may lead to the signal-tower. This is simply illustrative of any convenient coupling of the operative mechanism of the trip and semaphore. When so coupled, whenever the semaphore is set at "safety" the trip is idle, and whenever the semaphore is active the trip is also active.

In Fig. 5 the arm E on the locomotive, which engages the trip, is mounted loosely on the shank of a valve-plug e. A ratchet-wheel e' is rigid with this shank, while a spring-pressed pawl e^2 is secured to the arm E. By this means an actuation of the arm gives the valve-plug a partial rotation, and when the arm drops back the plug is left undisturbed. The return movement of the arm being idle, the arm may be so arranged that every alternate movement of it opens the air-pipe to apply the brake or operate a cab-signal. As shown in the drawings, there are eight teeth to the ratchet e', and the plug e is arranged with four openings. When any of these openings register with the corresponding opening in the valve-casing, the brake is applied or the signal operated. In the four intermediate positions the pipe is closed. A suitable connection, as a wire H, runs from the arm E up into the cab. When the arm E encounters the cautionary trip, it is moved thereby to open the pipe which may apply the brake. Then the engineer by simply pulling on the wire H turns the plug another notch, which closes the pipe, releasing the brake or shutting off the signal. By means of this cautionary trip the engineer is notified to run under control, but is allowed to proceed without stopping his locomotive, which is a decidedly advantageous feature, saving much time. If desired, the valve-plug e may be so arranged that at the cautionary points it directs the air to the engineer's whistle, while at the danger-points it applies the brake directly.

By my system no derailing-switch is necessary at railroad-crossings, for my trip automatically stops the train. With my invention the engineer may feel absolutely safe in

approaching a railroad crossing or switches even in a thick fog and at high speed.

I claim—

1. The combination of a spring-bar having a pair of supporting-legs rigidly secured to railroad-ties, and means on the locomotive adapted to engage the upper surface of said bar, and means for holding said bar down in idle position.

2. A spring-bar bent to present an upward bulge and inwardly-extending legs whereby the upper surface of the bar may be inclined upward in front of an approaching train or may be drawn down into idle position, combined with a rock-shaft for drawing the bar into such idle position.

3. In a train-controlling device, the combination of a spring-trip located at the track and an arm on the locomotive adapted to control an air-pipe, said arm being adapted to engage the upper surface of the trip and be swung thereby and means for bending the spring-trip downward out of the path of said arm.

4. In a train-controlling system, the combination of a spring-trip consisting of a bar normally bulging upwardly and having supporting-feet approaching each other, and a rock-shaft connected with said bar to draw it down to idle position, and an arm on the locomotive adapted to engage the upper surface of the bar.

5. A trip comprising a bar of spring metal bent to present intermediately an upward bulge and having its two ends bent downwardly and inwardly for feet, there being a downwardly-depending member on the under side of the intermediate part of the bar, and a rock-shaft engaging such member to draw the trip down into idle position.

6. In a train-controlling device, the combination of a trip located at the track and an arm on the locomotive adapted to control an air-pipe, said arm operating to open the pipe on alternate actuations, and means under the control of the engineer for giving intermediate actuations to said arm.

7. In a train-controlling system, a spring-trip consisting of a bar normally bulging upwardly and having supporting-feet approaching each other, and a rock-shaft connected with said bar to bend it down to idle position, combined with a semaphore and a common operating system for the semaphore and trip.

In testimony whereof I hereunto affix my signature in the presence of two witnesses.

JOHN C. HARDENBERGH.
